ZIGZAG SEWING MACHINE ATTACHMENT

Abraham Gellman, New York, and Sidney Diesenhaus, Monsey, N. Y., assignors to Abe Gellman & Company, New York, N. Y., a corporation of New York

Application February 4, 1948, Serial No. 6,128

9 Claims. (Cl. 112—158)

1

This invention relates to sewing machines and more particularly to an attachment adapted to be applied to a zigzag sewing machine to cause the machine to sew a zigzag or straight stitch in a predetermined pattern.

It is an object of the present invention to provide an attachment for a conventional zigzag sewing machine that may be easily and effectively mounted on the machine and is capable of controlling the operation of the machine to produce a wide variety of patterns. It is another object of the invention to provide an attachment for so controlling the operation of such a machine as to permit various patterns to be sewed either with or without a filler thread. It is a further object of the invention to maintain a predetermined but adjustable relation between the movement of the needle bar of such a machine and movement of a filler thread in sewing such patterns. It is still another object of the invention to provide an attachment for a zigzag sewing machine to cause the machine to sew a zigzag stitch in an undulating pattern. It is a still further object of the invention to provide an attachment of this type that can be easily adjusted to vary such variables as the width of the zigzag stitch and the shape, amplitude and frequency of the undulations of the undulating patterns. Other objects of the invention will be in part obvious and in part pointed out hereafter.

The invention accordingly consists in the features of construction, combinations of elements and arrangement of parts as will be exemplified in the structure to be hereinafter described, and the scope of the application of which will be indicated in the following claims.

The many objects and advantages of the present invention may best be understood and appreciated by reference to the accompanying drawings which show apparatus incorporating a preferred embodiment of the invention and wherein:

Figure 1 is a side elevation view of a conventional zigzag sewing machine having an attachment incorporating the present invention mounted in operative position thereon;

Figure 2 is a top plan view of a portion of the structure taken on the line 2—2 as shown in Figure 1;

Figure 3 is a section taken on the line 3—3 of Figure 1 and showing the cross-head and the manner in which the different links are connected thereto;

Figure 4 is a section taken on the line 4—4 of

Figure 1 showing the mounting of the filler thread feed nozzle and its relationship to the needle bar;

Figures 5 and 5a show respectively a particular cam construction adapted to be used in the present attachment and the stitch pattern that is produced when this cam structure is employed; Figures 6 to 9 and 6a to 9a show respectively various modified cam structures and the corresponding stitch patterns that are produced when such cam constructions are used in the present attachment.

Similar reference characters refer to similar parts throughout the several views of the drawing.

Referring initially to Figures 1 and 4, the numeral 10 designates the main frame of a conventional zigzag sewing machine which, as best shown in Figure 4, supports a conventional presser foot 12 mounted on a presser foot bar 13 and adapted to cooperate in the usual manner with a throat plate 14 and feed dogs 16 to cause the material to be sewed to pass between the presser foot and throat plate. A needle bar 18 carrying the needle 20 is mounted in the usual manner on the frame 10 for oscillation perpendicular to the direction of movement of the material to be sewed to cause the machine to produce a zigzag stitch.

Mounted adjacent to presser foot 12 there is a filler thread feed nozzle 22 through which the filler thread 24 is fed. The nozzle 22 is fixed to a U-shaped arm 26 which (see Fig. 1) is rotatably supported in a pair of brackets 27 and 28 on the filler thread bar 30. The arm 26 passes through the brackets 27 and 28 as well as through a collar 29 which is positioned between the brackets and fixed to arm 26 by set screw 31 in such manner that arm 26 can rotate in the brackets but cannot move transversely thereof. The bar 30 is pivotally mounted on the frame 10 at 32.

The end of arm 26 that extends through brackets 27 and 28 is fixed to a lever 34, the upper end of which is connected by a spring 36 to the bar 30. The construction is such that the spring 36 urges arm 26 and lever 34 in a counterclockwise direction (as shown in Fig. 4). The rotation of arm 26 and lever 34 under the influence of spring 36 is limited by a screw 38 which is threaded through lever 34 and bears against the bar 30. The position of filler thread feed nozzle 22 with respect to presser foot 12 and needle 20 can be adjusted by adjustment of the screw 38. In its lowermost position, arm 26 bears against a rod 40 supported in a bracket 42 on the presser foot bar 13, and thus as the presser foot bar and

presser foot 12 are raised, the feed nozzle 22 is also raised against the action of spring 36.

The filler thread is supplied in the usual manner from a filler thread take-up 33 mounted on the frame 10 and passes through tension discs 35 to the nozzle 22.

The mechanism now to be described produces a controlled movement of the needle bar 18 and filler thread feed nozzle 22 to cause the machine to sew a zigzag stitch in an undulating pattern. The needle bar 18 is given a relatively rapid oscillatory movement of relatively small magnitude substantially perpendicular to the direction of movement of the material to be sewed to cause the machine to sew a zigzag stitch, and there is superposed on this rapid oscillatory movement a slower transverse movement of larger magnitude to produce the desired undulatory pattern. The filler thread feed nozzle 22 is likewise given a rapid oscillatory movement which is substantially perpendicular to the direction of movement of the material, and which corresponds to the rapid movement of the needle bar 18 but is 180° out of phase therewith and is of somewhat greater amplitude than the movement of the needle bar. Superposed on this rapid oscillation of the nozzle 22, there is a relatively slower movement of larger amplitude that corresponds with and is in phase with the slower movement of the needle bar 18. These combined movements cause the machine to sew a filled zigzag stitch in an undulating pattern.

Referring now to Figure 2, power to operate the mechanism of the present attachment is taken from a power or transverse shaft 46 which is a part of a conventional sewing machine. Near one of its ends the shaft 46 is provided with an eccentric 48 having a bearing surface that cooperates with a similar surface of a bearing ring 50 of a link 52. The construction is such that the rotation of shaft 46 causes eccentric 48 to rotate to give link 52 a relatively rapid horizontal reciprocating motion. The shaft 46 normally rotates $\frac{1}{2}$ revolution per stitch. The amplitude of the movement of link 52 may be adjusted by changing the eccentricity of eccentric 48 in known manner.

Referring now to Figure 3 of the drawings, the link 52 is provided at its other end with a bearing ring 54 that cooperates with a frusto-spherical bearing 56 of a cross-head generally designated as 58. The cross-head 58 includes a shaft 60 rotatably mounted in the arms 61 and 62 of a U-shaped bracket 63, and adapted to oscillate about a substantially vertical axis; a bearing support 64 fixed to shaft 60 between the arms 61 and 62 by a set screw 66, and supporting the bearing 56; and a block 68 fixed to the bottom of shaft 60. The reciprocating movement of link 52 is transmitted through bearing support 64 to shaft 60 to cause the shaft to oscillate about its axis.

The block 68 is internally bored to receive a ratio rod 70 that is held in place with respect to block 68 by a set screw 72 in such manner that the position of the rod 70 with respect to block 68 may be adjusted. At its opposite ends the ratio rod 70 is provided with the frusto-spherical bearings 74 and 76 that cooperate respectively with the bearing rings 78 and 80 of the links 82 and 84 respectively. As shown in Figures 2 and 4, the link 82 is connected to the filler thread bar 30 through a bearing ring 86 and frusto-spherical bearing 88, and the link 84 is

connected to the needle bar 18 through bearing ring 90 and frusto-spherical bearing 92.

As pointed out above the link 52 is given a reciprocating motion by the eccentric 48 and this motion of link 52 causes the cross-head 58 to oscillate about a vertical axis. The ratio rod 70 which is fixed to cross-head 58 is given an oscillatory movement in a horizontal plane, and this oscillatory movement is transmitted through links 82 and 84 to the filler thread bar 30 and needle bar 18 respectively. Thus the filler thread nozzle 22 and needle 20 are simultaneously oscillated at a relatively rapid rate but in opposite sense. The relative magnitude of the movement of the filler thread and the needle is determined by the position of ratio rod 70 with respect to block 68 and may be adjusted by means of set screw 72. Ordinarily the rod 70 is so positioned with respect to block 68 as to give the filler thread nozzle a movement of substantially greater amplitude than that of the needle 20.

Referring again to Figure 3, the cross-head 58 is oscillatable not only around a vertical axis but also around a horizontal axis. The bracket 63 is secured by a pin 94 to a shaft 96 that passes through and is rotatably supported in a supporting plate 98 and a journal bearing 99 fixed to the plate 98. A spacing collar 97 is provided on shaft 96 between plate 98 and bracket 63 to maintain proper spacing of the bracket and plate.

The plate 98 is mounted on the main frame 10 in any suitable manner such as by the stud bolts 103. Referring to Figure 2, the bolts 100 may be, for example, the bolts that in a conventional machine support the presser foot lever 102, and the plate 98 may be spaced from the lever 102 by the spacer nuts 104.

The shaft 96 is given a relatively slow controlled oscillatory movement by a mechanism now to be described, and this oscillation of shaft 96 is transmitted to cross-head 58 and, through ratio rod 70, to the needle bar 18 and filler thread feed nozzle 22. Thus the movement of the needle bar and filler thread feed bar produced by movement of shaft 96 is effectively superposed on the rapid oscillatory movement previously described. The slow movement is applied in the same sense to both the needle bar and filler thread bar.

Still referring to Figure 2, the power shaft 46 extends through plate 98 and is provided beyond the plate with a pinion 106 which, through a reducing gear train generally designated as 108, drives a cam 110 mounted for rotation on plate 98. The cam 110 (see Fig. 1) is provided with a track 112 that cooperates with a cam follower 114 on a cam follower lever 116 pivotally mounted on plate 98. The cam follower lever 116 has a slot 118 through which it is connected by means of a bolt 120 with the slot 122 of a lever 124. The arrangement is such that the relationship between levers 116 and 124 may be varied as desired by adjustment of bolt 120 in slots 118 and 122.

Referring to Figure 3 as well as to Figure 1, the lever 124 is fixed by screws 126 to a cap 128 which is in turn fixed to the end of shaft 96 by the set screw 130. The cap 128 abuts the end of bearing 99 and thus prevents axial movement of shaft 96. Thus oscillatory motion of cam follower 114 produced by rotation of cam 110 causes the shaft 96 to oscillate in a controlled manner and this oscillation of shaft 96 is transmitted to the cross-head 58.

The operation of the attachment of the present invention should be largely apparent from the

foregoing description thereof. Referring to Figure 2 the power shaft 46 rotates at a relatively rapid rate to produce relatively rapid reciprocatory motion of the link 52. This rapid oscillation of link 52 is transmitted through cross-head 58 to the links 82 and 84 and thus produces rapid oscillation of the filler thread and needle bar respectively. The movement of the filler thread and needle is in opposite sense and the filler thread moves a substantially greater distance than the needle.

Superposed on this relatively rapid oscillation of the needle and filler thread, there is a slower reciprocatory movement. The power shaft 46 through pinion 106 and reduction gearing 108 drives cam 110 at a relatively slow rate. Referring to Figure 1 the track 112 of cam 110 causes the follower 114 and lever 116 to move in a controlled manner. Motion of lever 116 is transmitted to lever 124 and thence by shaft 96 to the bracket 63 and cross-head 58. Thus the cam 110 and its follower 114 cooperate to produce a relatively slow oscillation of the cross-head 58 about a horizontal axis, and this slow oscillation is transmitted to both the filler thread and needle in the same sense. The resultant motion of the needle and filler thread causes the machine to sew a filled zigzag stitch in an undulating pattern.

The character of the pattern that is sewed may be varied by varying the construction of the cam 110. Figures 5-9 show various cam track constructions and Figures 5a-9a show respectively the patterns that are obtained with the several cams shown in Figures 5-9. It will be apparent that a wide variety of patterns can be achieved with the present apparatus.

Certain of the characteristics of the pattern may be changed without modifying the construction of the cam or substituting a different cam structure. For example, the frequency of recurrence of the pattern for a given machine speed may be varied by substituting for the pinion 106 a pinion having a different number of teeth. Also the amplitude of the pattern may be varied by adjusting the bolt 120 in the slots 118 and 122 to vary the relationship between lever 116 and lever 124. The amplitude of the pattern may be reduced to zero, i. e. the cam may be made inoperative, by moving bolt 120 until it registers with the axis of lever 116. In order to preserve the symmetry of the pattern and of the operation of the needle, this adjustment should be made when the needle is in its central position, and the parts are so positioned that the needle is in its central position when the levers 116 and 118 are in alignment. The ratio of filler thread movement to amplitude of the zigzag stitch may be varied by adjustment of ratio bar 70 in block 68 of the cross-head 58, and the amplitude of the zigzag stitch may be adjusted, and also reduced to zero, by changing the eccentricity of eccentric 48.

From the foregoing description it is apparent that the present structure permits attainment of the several objectives referred to above. The attachment may be easily applied to a conventional zigzag sewing machine and when so applied is capable of controlling the operation of the machine to produce a wide variety of patterns.

It is, of course, to be understood that the foregoing description is illustrative only and that various modifications may be made within the scope of the invention. The attachment is particularly useful in its application to zigzag machines and has been described as applied to such

a machine, although it is evident that the attachment may also be used with machines other than zigzag machines. Also the filler thread and its control mechanism may be omitted and an unfilled zigzag stitch produced in accordance with a predetermined pattern. The cam 110 is, in effect, a template and other types of templates may be substituted therefor.

Since many embodiments might be made of the present invention and since many changes might be made in the embodiment disclosed herein, it is to be understood that the foregoing description is to be interpreted as illustrative only and not in a limiting sense.

We claim:

1. An attachment for a sewing machine having a transverse shaft and a needle bar mounted for lateral oscillation by said shaft to cause said machine to sew zigzag stitching, said attachment comprising a cross-head mounted for rotative oscillation about a vertical axis and about a horizontal axis arranged at right angles with respect to one another, driving mechanism actuated by said transverse shaft for oscillating said cross-head about said vertical axis, a cam having a predetermined pattern, linkage mechanism in the rear of said sewing machine interconnecting said cam and said cross-head to cause oscillation of said cross-head about said horizontal axis to be controlled by said cam, driving mechanism for producing relative movement of said cam and said rear linkage mechanism to oscillate said cross-head about said horizontal axis, and further linkage mechanism connected to said cross-head and to said needle bar to transmit to said needle bar the oscillations of said cross-head about both said vertical and horizontal axes to cause said machine to sew zigzag stitching in a pattern bearing a predetermined relation to said predetermined pattern of said cam.
2. An attachment for a sewing machine having a transverse shaft and a needle bar mounted for lateral oscillation by said shaft to cause said machine to sew zigzag stitching, said attachment comprising a cross-head mounted for rotative oscillation about a vertical axis and about a horizontal axis arranged at right angles with respect to one another, driving mechanism actuated by said transverse shaft for oscillating said cross-head about said vertical axis, a cam having a predetermined pattern, linkage mechanism connected to said cross-head and having a cam follower cooperating with said cam to cause oscillation of said cross-head about said horizontal axis to be controlled by said cam, driving mechanism causing said cam to oscillate said cross-head about said horizontal axis, and further linkage mechanism connected to said cross-head and to said needle bar to transmit to said needle bar the oscillations of said cross-head about both said vertical and horizontal axes to cause said machine to sew zigzag stitching in a pattern bearing a predetermined relation to the configuration of said cam.
3. An attachment for a sewing machine having transverse shaft and a needle bar mounted for lateral oscillation to cause said machine to sew zigzag stitching and having filler thread feeding means mounted thereon, said attachment comprising a cross-head mounted for rotative oscillation about a vertical axis and about a horizontal axis arranged at right angles with respect to one another, driving mechanism actuated by said transverse shaft for oscillating said cross-head about said vertical axis, a cam having a prede-

terminated pattern, linkage mechanism in the rear of said sewing machine interconnecting said cam and said cross-head to cause the oscillations of said cross-head about said horizontal axis to be controlled by said cam, linkage mechanism in the front of said machine connected to said cross-head and to said needle bar to transmit to said needle bar oscillations of said cross-head about both said vertical and horizontal axes to cause said machine to sew zigzag stitching in a pattern that bears a predetermined relation to said predetermined pattern of said cam, and further linkage mechanism in the rear of said sewing machine connected to said cross-head and to said filler thread feeding means to transmit to said filler thread feeding means oscillations of said cross-head to cause said filler thread feeding means to move in predetermined relation to the movement of said needle bar.

4. Apparatus as defined in claim 3, wherein said cross-head includes a ratio rod swingable about said vertical axis and said needle bar linkage and said filler thread linkage mechanisms are connected to opposite ends of said ratio rod.

5. Apparatus as defined in claim 3, wherein said cross-head includes a ratio rod swingable about said vertical axis and said needle bar linkage and said filler thread linkage mechanisms are connected to opposite ends of said ratio rod, and said ratio rod is adjustable to adjust the relationship between movement of said needle bar and movement of said filler thread feeding means.

6. An attachment for a sewing machine having a transverse shaft and a needle bar mounted for lateral oscillation to cause said machine to sew zigzag stitching and having filler thread feeding means mounted thereon, said attachment comprising a cross-head mounted for rotative oscillation about a vertical axis and about a horizontal axis arranged at right angles with respect to one another, driving mechanism actuated by said transverse shaft for oscillating said cross-head about said vertical axis, a cam, linkage mechanism connected to said cross-head and having a cam follower cooperating with said cam to cause said cam to control oscillations of said cross-head about said horizontal axis, driving means for driving said cam to oscillate said cross-head about said horizontal axis, linkage mechanism in the front of said machine connected to said cross-head and to said needle bar to transmit to said needle bar oscillations of said cross-

head about both said vertical and horizontal axes to cause said machine to sew zigzag stitching in a pattern bearing a predetermined relation to the configuration of said cam, and linkage mechanism in the rear of said machine and connected to said cross-head and to said filler thread feeding means to transmit to said feeding means oscillations of said cross-head to cause said filler thread feeding means to move in predetermined relation to the movement of said needle bar.

7. Apparatus as defined in claim 6, wherein said cross-head includes a ratio rod swingable about said vertical axis and said needle bar linkage and said filler thread linkage mechanisms are connected to opposite ends of said ratio rod.

8. Apparatus as defined in claim 6, wherein said cross-head includes a ratio rod swingable about said vertical axis and said needle bar linkage and said filler thread linkage mechanisms are connected to opposite ends of said ratio rod, and said ratio rod is adjustable to adjust the relationship between movement of said needle bar and movement of said filler thread feeding means.

9. An attachment for a sewing machine having a needle bar mounted for lateral oscillation to cause said machine to sew zigzag stitching, said attachment comprising a cam, a cam follower cooperating with said cam and including a slotted member, a linkage mechanism including a further slotted member connected to the slotted member of said cam, said further slotted member being connected to said needle bar, means for oscillating said needle bar to cause said machine to sew zigzag stitching, and driving mechanism for driving said cam to cause said linkage mechanism and needle bar to be moved by said cam and thereby cause said machine to sew zig-zag stitching in a pattern conforming with the configuration of said cam, the connection between said two slotted members being adjustable to adjust the width of said pattern.
